UNITED STATES PATENT OFFICE.

EDWARD CLARK, OF NEW YORK, N. Y.

LIFE-SAVING RAFT.

SPECIFICATION forming part of Letters Patent No. 585,508, dated June 29, 1897.

Application filed November 12, 1896. Serial No. 611,832. (No model.)

To all whom it may concern:

Be it known that I, EDWARD CLARK, of New York city, in the county and State of New York, have invented a new and Improved 5 Life-Saving Raft, of which the following is a full, clear, and exact description.

The object of the invention is to provide a new and improved life-saving raft for use on marine vessels in case of emergency, to permit 10 a number of persons to keep afloat and propel the raft to a place of safety.

It relates to that form of raft in which parallel elongated floats or buoyant chambers are connected together by an intermediate 15 framework; and it is designed to provide a very simple, strong, and practical construction of raft of this type.

The invention consists of certain parts and details and combinations of the same, as 20 will be fully described hereinafter and then pointed out in the claims.

Reference is to be had to the accompanying drawings, forming a part of this specification, in which similar characters of reference indicate 25 corresponding parts in all the figures.

Figure 1 is an inverted plan view of the improvement. Fig. 2 is a side elevation of the same. Fig. 3 is an enlarged transverse section of the same on the line 3 3 of Fig. 2. 30 Fig. 4 is a face view of one of the sides of one of the floats, and Fig. 5 is an enlarged transverse section of one of the floats on the line 5 5 of Fig. 2.

The improved life-saving raft is provided 35 with a boat A, preferably made in the shape of a flat-bottomed row-boat, as indicated in the drawings. On the sides of the boat A are arranged floats B B, each made straight and secured by straps C between the rails A' and 40 cross-beams A² of the boat A, the said cross-beams extending under the bottom of the boat, as plainly indicated in the drawings.

Each of the floats B is made square in cross-section at or near its middle and rectangular 45 in cross-section from the middle to the ends, as indicated in the drawings. Each float is set on edge, so as to present a V-shaped bottom to the water, the lower portion of each float extending a suitable distance below the 50 bottom of the boat A, so that the said bottom is carried at or above the level of the water. (See Fig. 3.) This setting of the V-shaped edge of the float also has a special value in relation to the mode of connecting the floats 55 to the boats, for it brings one set of ends of the

encircling straps C into a horizontal position for connection to the cross-bar under the bottom of the boat and the upper set of ends into a nearly vertical position for connection with the rail along the upper edge of the boat, thus 60 causing the floats to be connected to the strongest portions of the boat-frame and enabling the boat to safely hold its load without resting upon the water at all.

By the arrangement described the inner 65 sides of the V-shaped bottom of each float B stands at an obtuse angle to the horizontal plane of the boat and the level of the water, whereby great stability is obtained for the raft.

The floats B are rendered completely water-tight and are of such size as to support the boat A and a large number of persons without danger of upsetting the raft. The boat may be provided with suitable seats, oars, or other propelling mechanisms to enable the occupants to propel the boat to a place of safety, it being understood that the boat can be readily propelled through the water, owing to the V-shaped bottoms of the floats B B. 75

Having thus fully described my invention, 80 I claim as new and desire to secure by Letters Patent—

1. A life-saving raft comprising a flat-bottom boat having cross-bars beneath its bottom, parallel floats arranged upon each side 85 of the boat in longitudinal position, and transverse straps encircling the floats and having one set of ends emerging therefrom horizontally and connected to the cross-bars beneath the boat, and the other set of ends extending 90 upwardly from the top of the floats and connected to the upper rail of the boat, substantially as and for the purpose described.

2. A life-raft comprising a flat-bottom boat having cross-bars beneath its bottom, parallel floats of rectangular cross-section set on the angles and one arranged upon each side of the boat in longitudinal position, and transverse straps encircling the floats and having one set of ends emerging therefrom horizontally and connected to the cross-bars beneath the boat, and the other set of ends extending 100 upwardly from the top of the floats and connected to the upper rail of the boat, substantially as and for the purpose described.

EDWARD CLARK.
